(57) **CLAIM**

The ornamental design for a front fairing for a motorcycle, as shown and described.

DESCRIPTION

FIG. 1 is a front perspective view of the front fairing for a motorcycle;

FIG. 2 is a front elevation view of the front fairing for a motorcycle;

FIG. 3 is a rear elevation view of the front fairing for a motorcycle;

FIG. 4 is a left side elevation view of the front fairing for a motorcycle;

FIG. 5 is a right side elevation view of the front fairing for a motorcycle;

FIG. 6 is a top plan view of the front fairing for a motorcycle; and,

FIG. 7 is a bottom plan view of the front fairing for a motorcycle.

The bolt/screw holes along the top edge of the fairing in FIGS. 1-7 are shown in broken line phantom and form no part of the claimed design.
